UNITED STATES PATENT OFFICE.

SYDNEY TEMPLETON FARRELL, OF NEWTON, MASSACHUSETTS.

GAME.

Application filed January 23, 1925. Serial No. 4,222.

The invention to be hereinafter described relates to games and more particularly to a miniature, indoor baseball game.

Heretofore, so far as I am aware, such 5 baseball games have been designed principally with respect to the performance of the pitcher and batter, and with little or no consideration to the performance of the base 10 runners, fielders and other phases of the game.

One of the purposes of this invention, therefore, is to simulate as fully as possible in a miniature, indoor baseball game, the 15 plays and conditions of the actual, outdoor game. In accomplishing this, consideration is given to the different plays which can be made when any one of the eight possible base conditions exists. These conditions are 20 as follows: (1) bases clear, (2) runner on first, (3) runner on second, (4) runner on third, (5) runners on first and second, (6) 25 runners on second and third, (7) runners on first and third, and (8) runners on first, second and third.

In the present instance of the invention, the possible plays for the different base 30 conditions are presented by short descriptions on a chart and cooperating with this chart is a device which is adjustable in response to or in accord with each new base condition, thereby to select from the chart a group of 35 plays, any one of which is possible when such base conditions exists. Also a device is provided which may be operated to determine by chance which play of the selected group of plays shall be the next play.

Each play is given in such a way that 40 every player who figures in the play either offensively or defensively, is given credit for what he does as in a regular game. Impossible plays or any which would be foreign to the regular game cannot occur.

The game comprises the above and other 45 devices, a description of which will herein- after appear.

One good form of the invention is shown in the accompanying drawings, wherein:

Fig. 1 is a perspective view of the device 50 for selecting groups of plays possible for the different base conditions;

Fig. 2 is an end elevation of the device shown in Fig. 1, portions being broken away;

Fig. 3 is a plan of the dial and indicator device;

Figs. 4 and 5 taken together present the 55 plays on one section of the chart, the union of the portions of the chart in said figures being indicated by dot and dash lines in said figures;

Fig. 6 on an enlarged scale is a development of the marked surface of the base 60 condition indicator; and

Fig. 7 is a plan of the board having the 65 baseball diamond, the dial and pointer, the score slates and other devices thereon.

Referring to the drawings, the baseball 70 game shown therein as illustrative of one good form of the invention, as stated, comprises a device for selecting groups of plays on a chart which are possible for different base conditions. This device includes a support 1 (Fig. 1) on which is mounted a chart 3 (Figs. 4 and 5) presenting brief descriptions of numerous plays which are arranged 75 in groups, there being 24 plays which are possible for each of the eight above-mentioned base conditions, making a total of 192 plays. For convenience, the plays of each group are presented in two horizontal lines 80 on the chart, each of which lines contains twelve plays. The 192 plays presented in Figs. 4 and 5, occupy one section of the chart, and a similar collection of plays occupies another section of the chart. The 85 plays of the two sections are the same, but the printing of the descriptions thereof is so disposed that the descriptions may be read by opponents sitting at opposite ends of the chart. The horizontal lines of plays on the section of the chart shown are designated by the letters *a* to *p*. These same lines would appear on the opposite section of the chart, but in the order *b* to *p*, *a*, reading from the line nearest the end of the chart toward the 90 center of the chart, that is, the row nearest the end of the chart would correspond to row *b*—*b* appearing in Figs. 4 and 5, and the row nearest the center of the chart would correspond to row *a*—*a* appearing in said figures. 95

A slide 5 is over the chart, and comprises a plate 7 secured to runners 9 having grooves at the lower edges thereof mating with ribs at the upper edges of rails 11 on the support 1. The plate is apertured to disclose groups 100 of plays on the chart, and in the present in-

stance, above each of the opposed chart sections are elongated apertures 15 and 17. On the plate adjacent each aperture 15 is a series of play identifying numbers 1 to 12, 5 and on the plate adjacent each aperture 17 is a series of play identifying numbers 13 to 24, the second series in effect constituting a continuation of the first series.

Suitable means may be provided to adjust 10 the slide relatively to the chart, in the present instance, comprising a pair of racks 19 meshing with gears 21 on a shaft 23 mounted in bearings on the support 1. At opposite ends of the shaft are cup-shaped wheels 25 15 having knurled peripheries. End portions of the shaft 23 project beyond the gears 21 away from the sides of the slide and have spools or drums 27 fast thereon, each marked with the eight base conditions as appears on 20 an enlarged scale in the development of the surface of spool appearing in Fig. 6. Each of the spools is received by a shell 29 having an aperture 31 through which the base conditions may be exposed one at a time. The 25 printing of the base conditions on the spools is so disposed that it may be read by the opponents sitting at opposite ends of the chart. A pair of fingers 33 project up from the base and have portions overlying the slide plate, 30 in order to hold the runners down onto the rails and to prevent the racks 19 from getting out of mesh with the gears 21.

The construction is such that on the occurrence of each new base condition, one or 35 the other of the opponents rotates one of the knurled wheels 25 in order to render visible at the shell apertures 31 the description of that base condition. For example, in Fig. 1 an adjustment has been made which brings 40 at the shell aperture the base condition,— "bases clear." This adjustment has shifted the slide so that the apertures 15 and 17 therein will disclose the plays on the chart which are possible when the bases are clear.

45 Next will be described a convenient device which is operable to determine by chance which play of the group of plays selected as above described shall be the next play. This device comprises a dial 35 (Fig. 3) which may be marked with radial lines dividing the dial into spaces 37. Some of these spaces may be marked with numbers from 1 to 24 corresponding to the numbers 50 on the slide, and others of these spaces may be marked with the words "Ball" and "Strike." The dial has circular lines which 55 form sub-divisions 39 of the spaces between the radial lines. Each of the numbers and each of the words may appear in three different positions. For example, the number 60 14 may appear in one of the spaces between the radial lines and in the two sub-divisions of said space formed by the circular lines, and in the sub-divisions the numbers face 65 in opposite directions. The arrangement of

the numbers and the words is such that they can be easily read from any angle.

At the center of the dial is a button 41 through which passes a pin 43, and mounted thereon is a pointer 45 which may have a 70 flexible element or whisker 47 of rubber or other suitable material. At the juncture of the radial lines with one of the circular lines referred to, are pins 49. The construction is such that when the pointer spins, the 75 whisker will wipe past the pins, and when the pointer comes to rest, it will always be in a position between a pair of pins.

The spaces between the radial lines are of unequal widths, the widest divisions being 80 marked "Ball" and "Strike." The narrower divisions are marked with numbers identifying plays, and the widths are determined with consideration to giving the harder or more unusual plays the narrowest spaces. 85 In other words, the width of the spaces is proportioned to the difficulty of the plays.

After the slide has been adjusted to select from the chart the group of plays possible while a certain base condition exists, the 90 pointer is spun and allowed to come to rest, and the number or word at the space indicates the play which is to be made. If the pointer stops at a space marked "Ball" 95 or "Strike", such play is made without reference to the chart, but if the pointer stops at a space marked with a number, reference is had to the corresponding number on the slide, and the play indicated thereby on the 100 chart is the next play to be made.

To enable ready visualization of the plays, a miniature baseball diamond 51 may be laid out on a board 52 or other suitable support, and have the positions of the players and the umpires indicated thereon. At opposite 105 sides of the diamond are the players' benches 53 which will be occupied by the players in the order in which they come to bat. The players of each team may be represented by checkers 55, nine in number, 110 and having the numbers 1 to 9 on the tops thereof. When a play has been determined as above described, the checkers representing the runners in the play are placed on the diamond in their proper positions, and on 115 the next play the checkers are moved on the diamond to their new positions resulting from the play.

To record the balls, strikes and outs, tallies 57 may be set in recesses in the board and be 120 adapted to turn on pins 59. These tallies are in the form of buttons having points adapted to register with suitable numbers on the board adjacent to the buttons.

Back of the players' benches and at the 125 left of the tallies are spaces 61 which may be considered to represent the grandstands for the spectators watching the game.

The dial 35 referred to may be desirably set in a recess in the board on which the 130

diamond is marked, and directly to the left thereof. The pin 43 on which the pointer is mounted may be set in the board, and the pins 49 past which the pointer whisker wipes 5 may also be set in this board.

In order that the opponents playing the game may readily keep the score, a pair of slates 63 may be set in recesses in the board at opposite sides of the dial, and at the left 10 of the diamond. These slates are lined and marked with data whereby the score may be kept as will be readily understood by those conversant with the usual game of baseball. The matter on these slates is so 15 disposed that it may be read by the opponents sitting at opposite sides of the board.

The board having thereon the baseball diamond, checkers, tallies, dial and slates, may be placed in one side of a box, and the 20 device comprising the chart and slide may be placed in the opposite side of the box. These sides may be connected by hinges, so that when it is desired to play the game, the sides of the box may be opened so as to 25 disclose the devices therein. When the game is not in use, the sides may be closed and retain all of the devices of the game. Since the box is not a part of the invention, it has not been considered necessary to show 30 the same in the drawings.

To further explain the manner in which the game is played, one of the base condition indicators is adjusted so as to disclose "bases clear" in the shell aperture of the indicator, 35 since the game always starts with bases clear. This adjusts the slide to a position in which any of the twenty-four plays may be made which are possible under this base condition. These twenty-four plays are presented by the brief descriptions appearing in 40 lines *a—a* and *i—i* on the chart shown in Figs. 4 and 5.

To determine which of these twenty-four possible plays shall be the next play, the 45 pointer is spun on the dial. If it comes to rest at the space on the dial numbered 12, reference is made to the play on the chart identified by the number 12 on the slide, and this is found to be "two base hit, batter takes 50 second." Then the checker numbered 1 is placed on second base on the diamond to show that this play has been made.

As stated, the slide should be adjusted in 55 response to each new base condition. Therefore, since the bases are no longer clear and there is a runner on second base, the slide must be adjusted. The indicator is turned until "Runner on second" appears at the aperture in the indicator shell. This adjustment of the slide discloses the plays appearing on lines *o—o* and *g—g* on the chart.

Then the pointer is again given a spin, and if it stops at the space numbered 15 on the 60 dial, reference is made to the description of the play on the chart identified by number

15 on the slide, and this is found to be "batter out, third base to first base, runner on second advances to third base." Since the player represented by checker No. 1 has reached third base, this checker is placed on 70 third base on the diamond.

The base condition is now changed again, and therefore, the indicator is adjusted so that "Runner on third" appears in the aperture of the indicator shell. This adjusts the 75 slide to a position to disclose the twenty-four plays which may be possible under this base condition.

If after the pointer is given a spin it comes to rest at a space on the dial marked "Ball", 80 reference to the chart is unnecessary, and the tally registering balls is adjusted to point to 1. Similarly, if the pointer after being given a spin comes to rest at a space on the dial marked "Strike", reference to the chart 85 is unnecessary, and the strikes is adjusted to point to 1.

Thus, in this fashion the game is played until one of the sides has three outs. Then the other side comes to bat. Each event of 90 the game may be recorded on the slates.

To facilitate scoring of the plays, the parts of certain of the descriptions of plays may be graphically differentiated. This may be accomplished by underscoring portions of 95 the descriptions of the plays, or it may be accomplished by printing such portions in red and black ink.

To further facilitate scoring of the plays, certain of the descriptions of plays may be 100 accompanied by code indicia. The presence of an asterisk in a space containing a description of a play signifies that if two men are out and two strikes are on the batter, the second part of the play is not to be scored, since the side is out before the man is caught off base. The presence of a small square in a space containing a description of a play signifies that if less than two men are out before the play described is started, the batter should be credited with a sacrifice hit. The presence of a small circle containing a cross in a space containing a description of a play signifies that if there are any out before the play described is 115 started, the run is not to be counted.

In order to illustrate the use of the differentiated portions of the descriptions of certain of the plays and the code indicia in 120 certain of the spaces, the following example may be considered.

One of the most difficult plays to score 125 reads on the chart as follows.—double play, runner on first and batter out, 2 B. to S. S. to 1 B., runner on second takes third, runner on third scores. A circle containing a cross appears in the space in which this play is described.

This play covers the following situation 130 during a game. There are three men on

bases. The man at bat hits a ground ball to the second baseman. The second baseman scoops it up and tosses it to the shortstop who covers second. This forces out the 5 runner occupying first base before the play started. In the meantime the runner on second has a big lead off that base and makes third safely, and the runner on third also having a big lead, safely reaches home and 10 scores a run. However, the shortstop after making the put-out on the man running from first, seeing that there is no chance to catch the other two runners, throws the ball to the first baseman in time to put out the 15 batter and complete a double play.

If there is nobody out at the time this play occurs, the entire description of the play in the space would be considered, and the play would be scored as follows. The 20 batter would be charged with a turn at bat. The second baseman would be credited with "assist." The shortstop would be credited with a "put-out" and an "assist." The first baseman would be credited with a "put-out." 25 And the runner on third would be credited with scoring one run.

On the other hand, if there is one man out at the time this play occurs, the entire description of the play appearing in the space 30 in question would be taken into consideration, and the entire play would be scored the same as above, with the exception of crediting the runner on third with a run. This is signified by the small circle containing a 35 cross at the end of the description of the play, which refers to the code or rule given above stating that if there are any out before this play is started, the run does not count. Since one man is already out before the play 40 is started, the double play makes it three out, and therefore, the side which has been at bat is retired, and the run does not count.

If there should be two out when the play 45 in question occurs, only the underscored portion of the description of the play is considered. This would make the play read as follows. Runner on first out, 2 B. to S. S. The play would be scored as follows. Batter is charged with a turn at bat. Second base- 50 man is credited with an "assist." And shortstop is credited with a "put-out".

This put-out being the third out of the 55 inning would retire the side at bat without any further play. It is in a case of this kind that the underscored portion and the remaining portion of the description of a play features, as it will not be necessary to read the whole play in order to see at once which is the first man to be put out in any double 60 play, and what player makes the "put-out" and "assist" when there is one.

While the invention has been described more particularly with respect to a baseball game, it will be understood that some features thereof are applicable to other games.

It will be understood that the invention is not limited to the specific embodiment shown, and that various deviations may be made therefrom without departing from the spirit or scope of the appended claims. 70

What is claimed is:

1. In a game, a chart having numerous plays described thereon, an adjustable slide over the chart having elongated apertures and numbers along and adjacent to said apertures, said slide being adjustable in response to each new play condition to disclose through said apertures only plays on the chart which are possible while such play condition exists. 75

2. In a game, a chart having numerous plays described thereon, a slide over the chart apertured and adjustable to disclose different groups of plays which are possible when different play conditions exist, and means for indicating the different play conditions. 85

3. In a baseball game, a chart having numerous plays described thereon, means adjustable in response to each new base condition to select only plays which are possible when such base condition exists, and means for determining the adjustment of said means including a spool having the different base conditions marked thereon. 90

4. In a baseball game, a chart having numerous plays described thereon, means adjustable in response to each new base condition to select only plays which are possible when such base condition exists, means for determining the adjustment of said means including a spool having the different base conditions marked thereon, and a shell receiving said spool having an aperture through which said different base conditions may be seen one at a time. 95

5. In a baseball game, a chart having numerous plays described thereon, a slide over the chart apertured and adjustable to disclose different groups of plays which are possible when different base conditions exist, and means including a rack and gear for adjusting said slide to present the proper group of plays for each base condition. 110

6. In a game, a support, a chart on said support having numerous plays described thereon, and a slide having runners movable along said support, said slide being apertured and adjustable to disclose different groups of plays on the chart which are possible when different play conditions exist. 115

7. In a game, a chart having a pair of sections with numerous different plays described on said sections, said sections having the same plays thereon, but in reversed relation so that the matter on the two sections may be read from opposite sides of the chart, and a slide over said chart adjustable in response to each new play condition and 125 130

having apertures over said sections through which may be disclosed only plays on the chart which are possible while such play condition exists.

5 8. In a game, a chart having numerous different plays described thereon, means adjustable in response to each new play condition to select a group of plays on the chart, any one of which is possible when such play
10 condition exists, said adjustable means having numbers identifying the plays of the group; and a device having numbers corresponding to the aforesaid numbers, and means to select one of said numbers by
15 chance, thereby to determine which one of the plays of the selected group of plays shall be the next play.

9. In a baseball game, a chart having numerous different plays described thereon, means adjustable in response to each new base condition to select a group of plays on the chart, any one of which is possible when such base condition exists, said means having numbers identifying the plays of the
20 group, a dial having thereon numbers corresponding to the aforesaid numbers and having marked thereon the words "Ball" and "Strike", and a pointer adapted to be
25

spun and come to rest at one of said numbers or words, thereby to determine which play
30 shall be the next play.

10. In a baseball game, a chart having arranged thereon eight groups of descriptions of plays corresponding to the eight possible base conditions, the description of plays of each group being possible for a particular base condition, and selective means to render
35 said groups singly visible on the chart.

11. In a baseball game, a pair of charts, each having arranged thereon eight groups of descriptions of plays corresponding to the eight possible base conditions, the descriptions of plays of each group being possible for a particular base condition, and said charts being disposed to be read by two persons facing each other.
40

12. In a baseball game, a dial divided into spaces, some of which bear numbers while others bear the words "Ball" and "Strike", said numbers and words being marked on the dial in a plurality of positions 50 in each space to facilitate reading of the same from any angle, and a pointer rotatably mounted on the dial and adapted to be spun and to come to rest at any one of said spaces.
45

SYDNEY TEMPLETON FARRELL.

CERTIFICATE OF CORRECTION.

Patent No. 1,667,147.

Granted April 24, 1928, to

SYDNEY TEMPLETON FARRELL.

It is hereby certified that error appears in the printed specification of the above numbered patent requiring correction as follows: Page 3, line 86, before the word "strikes" insert the words "tally recording"; and that the said Letters Patent should be read with this correction therein that the same may conform to the record of the case in the Patent Office.

Signed and sealed this 29th day of May, A. D. 1928.
